UNITED STATES PATENT OFFICE.

Patent issued to LOUIS KANTROWITZ, OF NEW YORK, N.Y. for an improvement in spark plugs, especially for internal combustion engines, and to have and to hold exclusive right in the United States to his invention, which is described in the following specification, reference being had to the accompanying drawings, forming a part hereof.

No. 888,711, issued under the Specification of Letters Patent. Patented May 26, 1908.

Application filed March 6, 1907. Serial No. 360,931.

To all whom it may concern:

Be it known that I, LOUIS KANTROWITZ, a citizen of the United States, and a resident of the borough of Manhattan, of the city of New York, in the county and State of New York, have invented certain new and useful Improvements in Sparking Plugs, of which the following is a specification, reference being had to the accompanying drawings, forming a part hereof.

The object of the invention is to provide a sparking plug for engines and the like in which the combustion is effected by means of an electric spark, in which sparking plug the electrodes shall not readily become short circuited. As is well known, the carbonizing of the electrodes and adjacent parts, which is caused by soot deposits during the operation of internal combustion engines, soon produces a path of lower resistance for the igniting circuit than that across the gap between the tips of the electrodes. The high tension current then passes through said path of lower resistance without producing the required spark. The spark plug thus fails to effect the ignition and has to be repaired or replaced.

In accordance with the present improvements, the insulation around one of the electrodes is provided with a vibratory or otherwise movable member or members in order to prevent the permanent lodgment of soot, and in the present case this is effected by surrounding one of the electrodes with non-conducting plates as will presently be described.

The invention will be more fully described in connection with the illustration in the drawings of a suitable embodiment of the invention.

In said drawings the single figure represents partly in section and partly in elevation, a sparking plug containing the improvements.

The plug may have the usual body or casting *a*, stem *b* and thumb nut *c*, which nut holds the stem and casing together. One of the electrodes *d* preferably projects from the inner end of the casing *a* and is covered with a suitable insulating material *e* which is extended up nearly to its tip. The other electrode *f* is preferably straight and projects substantially from the center of the stem of the plug. The stem may be made of porce-

lain or of any other suitable material and its inner end is preferably corrugated as shown.

Around the electrode *f*, a plurality of non-conducting plates *g* are mounted, being slightly separated from each other, as by still smaller disks *h*, and preferably forming a series of disks decreasing in size toward the end of the electrode *f*. The other electrode *d* may be curved so that its upper end or tip is brought within the proper distance from the end of the electrode *f*, the curvature of the electrode *d* conforming in general to the sloping of the edges of the series of disks.

The disks are formed preferably of mica and are mounted so as to be capable of vibrating or otherwise moving to a slight degree; and this may be accomplished by fitting them upon the electrode securely enough to retain them but not rigidly enough to prevent them from having some freedom of movement. In this way the jar produced by the operation of the engine will cause the disks to vibrate more or less. Means such as a washer *i* may be provided to retain the disks if necessary.

The provision of the disks, as will be obvious, will prevent the formation of soot across the inner end of the stem *b* between the electrodes, and the vibration of the disks will prevent the formation of a permanently lodged deposit thereon. The soot therefore cannot readily bridge itself across from one electrode to the other and thus cause a short circuit in the manner heretofore pointed out.

It will be clear that the disks may be more or less resilient and hence may vibrate sufficiently even when they are made quite tight to the electrode. However, it is preferable to mount them loosely upon the electrode, as was stated hereinbefore. It will be clear too that it will be possible to change the construction of the plug in many particulars without departing from the spirit of the invention.

I claim as my invention:

1. In a sparking plug, the combination of an electrode, and insulation around the same having a fixed portion and a vibrating portion.
2. In a sparking plug, the combination of an electrode and a plurality of non-conducting plates mounted to vibrate on the same and slightly separated from each other.
3. In a sparking plug, the combination of

an electrode, a plurality of non-conducting plates mounted to vibrate on the electrode and slightly separated from each other, and means for maintaining the plates upon the electrode.

4. In a sparking plug, the combination of an electrode projecting centrally therefrom, an electrode projecting from one side, and a plurality of plates of a non-conducting material mounted to vibrate on the first electrode and separated from each other.

5. In a sparking plug, the combination of a straight electrode projecting centrally therefrom, a curved electrode projecting from one side, and a plurality of non-conducting plates mounted to vibrate around the first electrode and slightly separated from each other.

6. In a sparking plug, the combination of an electrode, and a plurality of non-conducting disks mounted to vibrate around the electrode.

7. In a sparking plug, the combination of

an electrode and a series of non-conducting disks loosely mounted around the electrode and decreasing in size toward the end of the electrode.

8. In a sparking plug, the combination of a straight electrode projecting therefrom, a series of mica disks loosely mounted around the electrode and decreasing in size toward the end of the electrode, and a curved electrode projecting from one side.

9. In a sparking plug, the combination of the two electrodes, and an oscillating interrupter of non-conducting material on one of the electrodes to prevent the formation of a continuous line of soot between the electrodes.

This specification signed and witnessed this 2nd day of March 1907.

LOUIS KANTROWITZ.
